UNITED STATES PATENT OFFICE.

ALEXANDER DUNCAN, OF WHEATON, ILLINOIS.

GOLF-CLUB.

1,322,182.

Specification of Letters Patent. Patented Nov. 18, 1919.

Application filed December 13, 1918. Serial No. 266,523.

To all whom it may concern:

Be it known that I, ALEXANDER DUNCAN, a subject of the King of Great Britain, residing at Wheaton, county of DuPage, State of Illinois, have invented certain new and useful Improvements in Golf-Clubs, of which the following is a specification.

My invention relates generally to golf clubs and particularly to golf clubs having heads of wood, fiber, aluminum or other relatively light material, which are provided with additions of metal or other relatively heavy material to give the necessary weight and balance to the club. For convenience in description I will refer to that part of the club head consisting of wood, fiber, aluminum or other relatively light material as the "light section" and that part of the club head consisting of metal or other relatively heavy material as the "heavy section".

The principal objects of my invention are to so construct, dispose and arrange the heavy section as to produce the highest efficiency and the best results in the use of the club, and at the same time to simplify its manufacture and improve its durability.

In carrying out my invention I employ a light section which conforms closely to the shape of the finished club head, and a heavy section having a flat portion which fits into a groove in the light section extending from the front to the back of the head and formed in its under surface or sole, with an enlarged portion which fits into a cavity in the light section lying at the rear of and above the groove. In the cavity co-acting shoulders on the light section and the heavy section also co-operate in transmitting strain from the heavy section to the light section, and in preventing the heavy section from moving forward on impact with the ball. In the preferred construction the groove is somewhat wider at the back than at the front, as is the flat portion of the heavy section, and this construction assists in transmitting strain from the heavy section to the light section and in preventing the heavy section from moving forward on impact with the ball.

Heretofore in the construction of golf club heads, of the kind to which my invention applies, the necessary weight has commonly been in the form of metal inserts or attachments at the rear of the club head, but these have never extended across the sole to the face of the club in the space imme-

diate back of the effective striking face, leaving the heel and toe of the club unweighted, as in my invention. Another type of previous construction has been an application of the weight in the form of a metal plate to the sole only of the club head, which does not provide the necessary weight at the rear of the club head opposite the point of impact of the face of the club head with the ball, and when this metal plate extends from the heel to the toe of the club head, the weight does not attain a maximum of efficiency and power on impact of the club head with the ball as it does when the weight is located to the rear of the effective striking face of the club head. By the effective striking face of the club head I mean that part of the flat face within which a ball can be hit with substantially good results.

In my invention the heavy section has a disposition of the weight partly on the sole of the club head and partly at the rear of the club head, a further novel and distinguishing feature being that the portion of the weight on the sole does not extend from the heel to the toe of the club, but rather to that portion of the sole only which is to the rear of the effective striking face of the club head.

Some of the additional advantages of my invention are that the flat portion of the heavy section provides a sole plate which protects the club head from wear; that the flat portion extends up to the driving face and thus not only protects the club head at that point, but dispenses with the usual insert there of fiber or other material; that the flat portion provides a sufficient weight below the point of contact of the striking face of the club head with the ball, so that the ball is more easily and quickly gotten up; that the distribution of the weight of the heavy section is such as to give a balance to the club head which is especially effective in action; and that both the flat portion and the enlarged portion of the heavy section so dispose the weighting of the club that it extends from the striking face to the rear and up the back of the club head conforming in width substantially to the length of the effective striking face of the club head, producing the best results in applying to the ball the energy of the swing of the club.

The various features and advantages of

my invention will be more fully understood upon reference to the following detailed description taken in connection with the accompanying drawing and the scope of the 5 invention will be particularly pointed out in the appended claims.

Figure 1 is a perspective view of the head of a golf club constructed in accordance with my invention; Fig. 2 is a perspective 10 view of the heavy section of the head; Fig. 3 is a perspective view of the light section of the head viewed from the under side; Fig. 4 is a bottom view of the light section and the heavy section assembled; Fig. 15 5 is a longitudinal vertical section, taken on a plane indicated by the line 5—5 of Fig. 4, and Fig. 6 is a transverse vertical section taken on a plane indicated by the line 6—6 of Fig. 4. Throughout these views like 20 characters refer to like parts.

Referring to the drawing in detail, 10 designates what I have termed the light section of the club head. This light section conforms closely to the shape of the finished 25 head and is provided with the usual socket or scare construction at 11 by which the shaft of the club is attached and held. The under surface or sole of section 10 is provided with a shallow groove 12. This 30 groove extends from the front of the club head through to the back and may be of substantially uniform width, but in the preferred construction is somewhat wider at the back than at the front. At the back of 35 the club head the groove 12 communicates with a cavity 13. This cavity is shaped so as to provide a shoulder 14 which faces backward. The cavity also extends a slight distance on either side of the groove 12 and 40 provides an outline which conforms to the outline of the lead insert commonly found in golf clubs of the prior art.

The groove 12 and cavity 13 are provided for the reception of the heavy section 15, 45 composed of any suitable metal. This heavy section comprises a flat portion 16, which is of the same width and depth as the groove 12 and adapted to fit snugly into the latter. It also includes an enlarged 50 portion 17, which is preferably integral with the flat portion 16, but extends considerably above it and comprises a considerable mass, as more clearly illustrated in Fig. 6. The enlarged portion 17 completely 55 fills the cavity 13. The forward end of portion 16 is flush with the driving face 18 of the club head. The rear surface of the enlarged portion 17 is convex and shaped so as to accurately conform to the shape of the 60 back of the club head. A plurality of screws 19 pass through countersunk openings in the flat portion 16 of the heavy section 15 into the light section 10. Besides having the convex back or outer surface, the 65 enlarged portion 17 is provided with a for-

wardly facing shoulder 20, which co-operates with the shoulder 14 to transmit strain from the heavy section 15 to the light section 10. These shoulders transmit practically all of the strain, but are, of course, assisted to some extent by the wedge shape of the flat portion 16 (in preferred construction) and by the screws 19. The latter, however, would be insufficient to perform this function without the employment of 70 the co-operating shoulders 14 and 20. Without the shoulders 14 and 20, the flat portion 16 would exert such a pressure in service upon the screws 19 as to loosen them and render the club useless.

It will be seen that the flat portion 16 acts as a sole plate for the club head and thus protects it from wear in use. The forward end of the flat portion 16, by extending so as to have its forward edge flush with 80 the striking face 18, protects against excessive wear at this point of the club head and takes the place of the usual insert of fiber or other material, as above noted. The location of the enlarged portion 17 is such 85 as to bring the center of the mass of the heavy section high enough to apply an effective blow to the ball when struck by the club. The location of this mass at the back of the club head also brings the center 90 of gravity of the head an appreciable distance back of a plane passing through the axis of the shaft of the club and substantially perpendicular to the sole of the club. Of course, other distributions of the weight 95 of the heavy section might be made so as to vary the position of the center of gravity, but I have found that better results are obtained by an arrangement of the weight of the heavy section which brings the center 100 of gravity back of said plane, as specified. Another advantage in locating the mass at the rear is the advantage of the accessibility and ease of gouging out the cavity 13 so as to provide the shoulder 14. This is an advantage over constructions where co-operating shoulders are located near the middle of the light section 10 and must be dug out by working directly upon the sole of 10. Another advantage in the employment of 105 the enlarged portion 17 is that of providing a back surface, which will have the outward shape and appearance of the metal insert usually found in club heads of this type. Golfers are accustomed to the presence of 110 metal at this point in such clubs and the employment of the enlarged portion 17 provides a club head which meets all the expectations of the golfer in its appearance.

It will be observed that another advantage 115 of my construction resides in the fact that if it becomes necessary to balance a particular club head in a particular way by the addition of more metal, such metal may be placed in cavities formed in the light sec- 120 125 130

tion 10 beneath the heavy section 15 and when the latter is in place, the club head will retain the same appearance and will not in any way show disfigurement.

5 It will also be noted that my club head is simple in that it contains but two sections and the screws which are necessary to hold them together. These two sections can be easily manufactured and assembled. The 10 structure is also applicable to clubs of different designs and shapes, as will be obvious. The club head which I have produced should be distinguished from those club heads wherein a weighting plate extends completely from 15 the heel to the toe. Such weighting plates do not, as heretofore stated, produce the same effect as my invention, wherein the mass of the heavy section is located directly behind the effective striking face. My in- 20 vention is also to be distinguished from those club heads wherein a thin plate of metal is secured to the sole. In such cases the plate does not add materially to the weight of the club head and is not relied upon for weight, but merely to protect 25 its sole from wear. Other features and advantages of the invention will be apparent to those skilled in the art and need not be further enumerated.

30 What I claim as new and desire to secure by Letters Patent of the United States, is:

1. A golf club having a head comprising two sections, one of said sections being of 35 relatively light material and conforming to the shape of the finished head with the exception of a groove extending across the sole transversely of the shaft of the club and a cavity in the back of the head opposite the striking face, said groove and cavity being continuous and lying between planes substantially perpendicular to the sole and extending transversely of the shaft at the outer limits of the effective striking face, the other section being a weighting 40 section of relatively heavy material conforming to and secured in said groove and cavity. 45

2. A golf club having a head comprising two sections, one of said sections being of relatively light material and conforming to 50 the shape of the finished head with the exception of a groove extending across the sole transversely of the shaft of the club and a cavity in the back of the head opposite the striking face, said groove and cavity 55 being continuous and lying between planes substantially perpendicular to the sole and extending transversely of the shaft at the outer limits of the effective striking face, the other section being a weighting section 60 of relatively heavy material conforming to and secured in said groove and cavity, the part of said weighting section in said groove being of substantial thickness thereby disposing a substantial part of said weighting 65 section at the extreme end of the club and forming the lower part of the striking face.

3. A golf club having a head comprising two sections, one of said sections being of relatively light material and conforming to 70 the shape of the finished head with the exception of a groove extending across the sole transversely of the shaft of the club and a cavity in the back of the head opposite the striking face, said groove and cavity 75 being continuous and lying between planes substantially perpendicular to the sole and extending transversely of the shaft at the outer limits of the effective striking face, the other section being a weighting 80 section of relatively heavy material conforming to and secured in said groove and cavity, the part of said weighting section in said groove being of substantial thickness thereby disposing a substantial part of said weighting 85 section across the center of the sole transversely of the shaft and also causing the center of mass of the head to lie substantially forward of the rear side thereof.

In testimony whereof, I hereunto subscribe my name this 10th day of December, 1918.

ALEXANDER DUNCAN.
